UNITED STATES PATENT OFFICE.

LOUIS G. MOLINA, OF CHICAGO, ILLINOIS, ASSIGNOR OF ONE-HALF TO ELIAS L. WINDOM, OF CHICAGO, ILLINOIS.

CARBURETER.

1,107,693.

Specification of Letters Patent. Patented Aug. 18, 1914.

Application filed December 9, 1912. Serial No. 735,800.

To all whom it may concern:

Be it known that I, LOUIS G. MOLINA, a citizen of the United States, and a resident of the city of Chicago, county of Cook, and 5 State of Illinois, have invented certain new and useful Improvements in Carbureters, of which the following is a specification.

My invention relates to carbureters and has for its object the provision of an improved carbureter of simple construction and efficient in operation.

The invention consists in the combinations and arrangements of parts hereinafter described and claimed.

15 The invention will be best understood by reference to the accompanying drawings forming a part of this specification, and in which,

Figure 1 is a sectional view of a carbureter embodying my invention, Fig. 2, a top plan view of the same, and Fig. 3, a side elevation of the same.

The preferred form of construction as illustrated in the accompanying drawings 25 comprises a suitable casing 1 having a suitable float chamber 2 secured thereto in any usual or desired manner. This float chamber is provided with the usual float 3, valve 4 and operating lever 5 for controlling the 30 supply of fuel entering said chamber from supply pipe 6, as will be readily understood by those skilled in the art. Valve 4 is guided in a plug 7 which is held in the wall of chamber 2 by means of a set screw 8, and the valve 35 4 is provided with a stem 9 adapted to prevent disengagement with the valve seat, as will be readily understood. Plug 7 is provided with a dust cap 10 loosely resting thereon and adapted to prevent entry of dust 40 into said plug. Chamber 2 is provided with a drain passage 11 leading to a drain cock 11' and with a supply passage 12 leading to a needle valve 13.

A head 14 is slidably mounted on needle 45 valve 13, as indicated, said head 14 having a threaded connection with a spring held sleeve 15 arranged around and below an air inlet opening 16 leading into a mixing chamber 17 in casing 1. An air inlet casing 18 is 50 arranged around sleeve 15 and has its lower end turned inwardly to contact with the sides of sleeve 15 and form an annular shoulder 19 adapted to co-operate with head 14 to regulate the passage of air into mixing chamber 17 as will be readily understood.

By this arrangement it will be observed, that the head 14 may be readily adjusted to regulate the passage of air into mixing chamber 17 and at the same time is yieldably mounted so as to be capable of further opening. 60

Head 14 carries a yoke 20 which is connected by means of links 21 with levers 22 pivoted on opposite sides of casing 1. These levers 22 are in turn connected by means of links 23 with arms 24 rigidly connected with the operating arms 25 of the throttle or butterfly valve 26 which controls the passage of the charges from the carbureter. The connection between arm 24 and link 23 is effected by a pin 27 slidably engaging a slot 28 in link 23, said slot 28 being provided with a stop screw 29 by means of which the movement of pin 27 in slot 28 may be adjusted, and consequently the effect of the movements of arms 25 varied. By this arrangement, it will be observed, that upon operation of throttle valve 26 to open the same, head 14 will be depressed to further open the same and permit the entry of a larger quantity of air to mixing chamber 17, thus providing for the increased air necessary when the engine speeds up in response to the opening of throttle valve 26. Casing 1 is also provided with a supplemental air inlet opening 30 normally closed by means of a suction operating valve 31 which is normally held to its seat by means of a compression spring 32. Valve 31 is slidably mounted on a rod 33 which is secured to casing 1 by means of a set screw 34, the inner end of 65 said rod 33 being slidably mounted in an abutment member 35 which abuts the inner end of spring 32, as shown in Fig. 1. Abutment member 35 is threaded in a spring held supporting sleeve 36, mounted in casing 1, 70 as shown. By this arrangement, it will be observed, that abutment member 35 may be adjusted to vary the tension of spring 32 and thus vary the operation of valve 31, and also that supporting sleeve 36 may be moved 75 to vary the tension in spring 32 and consequently the operation of valve 31.

Supporting member 36 carries a yoke 37 connected by means of links 38 with levers 39 pivotally mounted on casing 1, as shown. 105. These levers 39 are pivotally connected at their upper ends with a block 40 which in turn is pierced by a threaded rod 41 provided with adjusting nuts 42. This rod 41 is rigidly connected with a substantially 110

U-shaped yoke 28 which is pivotally connected to the operating arms 25 for the throttle valve 26. By this arrangement, it will be observed, that upon operating throttle valve 26 to further open the same, supporting sleeve 36 will be moved outwardly, and the tension in spring 32 correspondingly relieved, thus increasing the effective operation of valve 31 to admit more air to casing 17 in order to meet the requirements of the increased speed of the engine due to the opening of throttle valve 36.

A latching lever 44 is pivotally mounted on screw 34 and is provided at its end with a lug or projection engaging a groove 45 in the hub of valve 31. By this arrangement it will be observed, that the lever 44 may be operated, either by the hand or by other suitable connection, to temporarily hold valve 31 against opening, such provision being made in order to prevent opening of valve 31 when the engine is being started, thus insuring a richer mixture.

At one side casing 1 is provided with a stop projection 46, and the corresponding lever 25 is provided with inwardly extending arms or lugs 47 arranged on opposite sides of projection 46. Each of the lugs 47 carries a set screw 48 adapted to contact with the corresponding side of projection 46. By this arrangement, it will be observed, that movement of valve 26 toward opening position in either direction, will be limited, and the ultimate position of said valve may be adjusted, as desired.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A carbureter comprising a casing and suitable means for supplying fuel thereto, there being an air inlet opening in said casing and a throttle valve controlling the passage of gases therefrom; a spring held sleeve surrounding said opening; a head adjust-

ably mounted on said sleeve and co-operating with the outer end thereof; a fuel nozzle extending through said head and into said sleeve; and an operative connection between said sleeve and said throttle valve, substantially as described.

2. A carbureter comprising a casing, there being an air inlet opening in said casing and a throttle valve controlling the passage of gases therefrom; a spring held sleeve surrounding said opening; a head adjustably mounted on said sleeve and co-operating with the outer end thereof; a fuel supply nozzle extending loosely through said head; and an operative connection between said sleeve and said throttle valve, substantially as described.

3. A carbureter comprising a casing, there being an air inlet opening in said casing and a throttle valve controlling the passage of gases therefrom; a stationary sleeve communicating at its upper end with said air opening; a spring pressed sleeve slidably mounted in said stationary sleeve; a stem having a fuel nozzle at its top and extending into said spring pressed sleeve; a head slidably mounted on said stem, adjustably connected with said spring pressed sleeve and adapted to co-operate with the lower end of said stationary sleeve to control the admission of air to said opening; and an operative connection between said head and said throttle valve, substantially as described.

4. A carbureter comprising a casing, there being an air inlet opening in said casing and a throttle valve controlling the passage of gases therefrom; a sleeve communicating at its upper end with said air opening and slidably mounted in said casing; a stem having a fuel nozzle at its upper end extending into said sleeve; a head slidably mounted on said stem, connected with said sleeve and co-operating with the portion of said casing around said air opening to regulate the passage of air to the latter; and an operative connection between said head and said throttle valve, substantially as described.

In testimony whereof I have signed my name to this specification in the presence of two subscribing witnesses.

LOUIS G. MOLINA.
